CLOSURE CAP FOR BOTTLES OR THE LIKE

Max Muller, Kusnacht, Switzerland, assignor to Neopac
AG., Oberdiessbach, Bern, Switzerland

Filed Dec. 22, 1958, Ser. No. 53,850

Claims priority, application Switzerland June 27, 1958

Term of patent 7 years

(Cl. D58—26)

Fig. 1

Fig. 3

Fig. 1 is an elevational view of a closure cap for bottles or the like showing my new design, a part of the cap being broken away to show the interior combination.

Fig. 2 is a side view in elevation of the closure cap of Fig. 1.

Fig. 3 is a top plan view of the closure cap of Fig. 1.
I claim:

The ornamental design for a closure cap for bottles or the like, as shown and described.
